UNITED STATES PATENT OFFICE.

CHALMERS S. BROWN, OF LIMA, OHIO.

LOCKING DEVICE.

Application filed May 12, 1922. Serial No. 560,402.

To all whom it may concern:

Be it known that I, CHALMERS S. BROWN, a citizen of the United States, residing at Lima, in the county of Allen and State of Ohio, have invented certain new and useful Improvements in Locking Devices, of which the following is a specification.

This invention relates to locking devices, and more particularly to locks for man hole covers.

An object of the invention is to provide a lock for man hole covers that may be readily released and will automatically engage the man hole frame when the cover is placed in position.

In the present invention, I provide a pivoted latch arranged beneath the man hole cover and adapted to engage a shoulder on the frame. The latch is designed to normally assume locked position and is provided with a control member pivoted adjacent thereto. The latch is released by lifting the free end of the control member and this member is provided with a recess 25 adapted to receive a tooth carried by the latch whereby the movement of the latch is limited by the control member and it is always retained in position to engage a portion of the frame when the man hole cover is inserted.

In the accompanying drawings, I have shown one embodiment of the invention. In this showing:

Figure 1 is a plan view.

Figure 2 is a vertical sectional view.

Figure 3 is a detail sectional view of the cover, showing the locking member in elevation.

Figure 4 is a perspective view of the locking member removed, and,

Figure 5 is a detail view of a key.

Referring to the drawings, the reference numeral 1 designates a man hole frame and 2 a man hole cover. As shown, the frame is provided with an enlarged annular portion 3 forming a seat 4 for the cover. The lower face of the enlargement forms a shoulder 5.

The locking device forming the subject matter of the present invention is arranged on the under side of the cover and is adapted to engage the shoulder 5. Any number of locking devices may be employed.

In the present instance, I have shown a cover provided with a pair of locking devices. As the construction of the locking

devices is identical, a description of one will suffice. The cover is provided with a pair of downwardly projecting arms 6, forming supports for the latch and control member. 60 As shown, the latch consists of a member 7 having an opening 8 therein for the reception of a pivot pin 9 passing through suitable openings in the arms 6 and arranged adjacent the bottom. The latch is provided 65 with a locking face 10 and is so arranged that it normally tends to swing outwardly toward the frame. It is further provided with a tooth 11 projecting from its upper face. A control member 12 is arranged 70 above the latch and pivotally mounted in the arms 6. As shown, this member is provided with an opening 13, adjacent one end for the reception of a pivot pin 14. It will be apparent that the tendency of the control 75 member is to swing downwardly to the position shown in Figure 2 of the drawings, and this tendency is increased by providing the free end of the control member with an enlargement 14'. The lower face of the 80 control member is provided with a recess 15, for the reception of a key. The cover is provided with suitable slots 16 adjacent each of the locking members for the insertion 85 of the key. As shown, the key consists of a rod 17 having a hook 18 formed on its lower end. The key may be provided with a suitable handle portion 19.

In operation, the tooth 11 is normally received in a recess 20 formed in the lower 90 face of the control member. The latch is provided with the greater portion of its weight on the outside of the pivot and tends to swing outwardly. This outward swinging is limited by the arrangement of the 95 tooth within the recess and the latch is prevented from swinging downwardly to an inoperative position. When the cover is inserted, the faces 10 of the latches engage the under surface or shoulder 5 of the enlargement 3 and the cover is locked in position. 100 To remove the cover, the key 17 is inserted through the slot 16 and given a half turn to engage the hook 18 in the recess 15 of the control member. The control member is 105 then lifted to the dotted line position shown in Figure 2 of the drawings and the latch is swung to inoperative position by the engagement of the tooth 11 in the recess 20. 110 By inserting a pair of keys and lifting the control members, the cover is unlocked and it may then be removed by further lifting of

the keys and the cover. By providing a control member pivoted as shown, and arranged beneath the cover, the movement of the latch is limited to a small arc and it is prevented from swinging downwardly to an inoperative position. It will be apparent that when the cover is removed, the latch would have a tendency to assume a position depending from the arms 6 and thus be inoperative were its movement not limited by the control member.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A locking device for man hole covers comprising a latch pivoted to said cover and adapted to swing outwardly by gravity, and a control member engaging said latch to limit its outward movement and retain it in an operative position.

2. A locking device for man hole covers comprising a latch pivoted to said cover and adapted to swing outwardly, and a pivotally mounted control member arranged above said latch and adapted to engage it to limit its outward movement.

3. A locking device for man hole covers

comprising a latch pivoted thereto and adapted to swing outwardly, the free end of said latch being provided with a tooth, and a pivotally mounted control member arranged adjacent said latch, said control member being provided with a recess adapted to receive said tooth to limit the movement of said latch.

4. A locking device for man hole covers comprising a pair of arms depending from said cover, a latching member pivotally mounted in the lower portion of said arms, said member extending upwardly and outwardly, and a control member pivotally mounted in the upper portion of said arms, said control member being adapted to engage said latching member to retain it in operative position.

5. A locking device for man hole covers comprising a pair of arms depending from said cover, a latch pivotally mounted in the lower portion of said arms, said latch extending upwardly and outwardly and being provided with a tooth on its upper end, and a control member pivotally mounted in said arms above said latch, said control member being provided with a recess for the reception of said tooth.

In testimony whereof I affix my signature in presence of two witnesses.

CHALMERS S. BROWN.
